VENETIAN BLIND BRACKET

Harry H. Nelson, New York, N. Y., assignor, by
mesne assignments, to Lorentzen Hardware
Mfg. Corp., New York, N. Y., a corporation of
New York

Application March 29, 1940, Serial No. 326,573

16 Claims. (Cl. 156—17)

This invention relates to Venetian blinds, and more particularly to mounting brackets which are affixed adjacent to the top of a window frame for supporting a Venetian blind.

Ordinarily, a Venetian blind is detachably suspended from a "head-bar" that is affixed adjacent to the top of a window frame. In some instances this "head-bar," or suspension bar, is omitted and the blind suspended directly from the window frame. This has resulted in the upper slat of the blind (the tilt slat, or "tilt-bar") being sometimes designated as the "head-bar," with corresponding confusion of terms. In this specification the term "head-bar" will be employed to designate the suspension bar that is located above the tilt-bar of the blind.

In many instances the head-bar is mounted on brackets, one placed on either side of the window frame. Associated with the head-bar is mechanism for tilting the blind and adjusting its height; and frequently this mechanism is concealed by a valance, often in the form of a board.

A general object of the present invention is to provide an inexpensive, mechanically adequate bracket for mounting a Venetian blind head-bar and valance.

Another object of the invention is to provide such a bracket which can be economically and satisfactorily fabricated from sheet-metal on a quantity production basis.

A further object of the invention is to provide such a bracket which is so constructed that brackets for different thicknesses, or heights, of head-bars can be assembled from the same standardized parts.

Still other objects are to provide improved means for securing the head-bar in place, and to provide such means which facilitate the placing of the head-bar on a pair of brackets.

An additional object is to provide a bracket which supports a curtain rod, in addition to supporting a head-bar and a valance.

Various detailed and specific objects will be apparent from the accompanying disclosure.

The drawings show two species of left-hand brackets embodying the present invention, i. e., brackets for supporting the left-hand ends of the head-bar and valance as viewed from the room side of the window. It will be understood that a right-hand bracket is also used with each Venetian blind to support the right-hand end of the suspension bar and valance. However, only the left-hand bracket has been specifically disclosed since it will be understood that the right-

hand bracket is of the same construction but of opposite hand.

Fig. 1 of the drawings is an isometric view of a bracket embodying the present invention, showing the valance holder or carrier in partially open position.

Fig. 2 is a side elevation of the same bracket with the valance carrier closed, and showing in section a head-bar and valance supported by the bracket.

Fig. 3 is a top plan view of the bracket as shown in Fig. 2 but without the valance and head-bar.

Fig. 4 is a side elevation of the same bracket with the valance holder or carrier in open position, and showing in section a head-bar and valance in partially inserted position.

Fig. 5 is an enlarged isometric view of the keeper shown in the preceding figures for holding the head-bar in position on the bracket.

Fig. 6 is a fragmentary vertical section illustrating the manner of assembling the keeper with the bracket.

Fig. 7 is an isometric view of a modified form of bracket and keeper embodying the present invention, the view showing the valance holder or carrier in partially open position.

Fig. 8 is a side elevation of the bracket shown in Fig. 7, with the valance carrier closed, and the view showing in section a head-bar, valance, and curtain rod supported by the bracket.

Fig. 9 is a fragmentary side elevation of the structure shown in Fig. 7, and showing the keeper in its uppermost position.

Fig. 10 is a fragmentary horizontal section on line 10—10 of Fig. 8.

Reference will first be had to Figs. 1 through 6.

A flat stamped sheet-metal plate 11 is provided at its rear edge with an integral vertical flange 12 which projects laterally at right angles to the plate. Pivoted at 14 to the lower forward corner portion of plate 11 is a valance holder or carrier designated as a whole by 15. A head-bar support designated as a whole by 16 has vertical leg portions 17 and 18 which are welded or otherwise suitably secured to plate 11, and also has a horizontal shelf portion 19 on which the end of the head-bar rests. Vertically slideable with relation to support 16 is a U-shaped head-bar keeper designated as a whole by 20.

For so-called "inside" mounting of a Venetian blind, plate 11 is placed against the inner or side face of the window jamb, i. e., the face of the jamb which is perpendicular to the plane of the window. Holes such as 21 (3 shown) are provided to receive screws for mounting the bracket

in such "inside" position. In the case of so-called "outside" mounting of a Venetian blind, the flange 12 is placed against the front face of a window frame, which front face is parallel to the plane of the window. It will be noted that the flange 12 terminates some distance above the bottom of plate 11, and this provides such clearance that the blind can be fully raised without the blind slats striking on the bottom of flange 12. In this connection, flange 12 is so stamped that its rear face is flush with the rear edge 11a of the plate 11. Thus, when the bracket is positioned against the front of the window frame and secured by screws inserted through holes 22 (3 shown), the edge 11a bears against the face of the frame and assists in supporting and positioning the bracket.

The valance holder or carrier 15 is preferably stamped from a single piece of sheet-metal and includes a front flange 24 and a rear flange 25 between which the valance 26 is inserted, as shown in Fig. 2. The valance carrier is also provided with a bottom flange 27 against which the bottom of the valance rests. An ear 28 is provided to make a pivotal connection at 14, and a rearwardly extending flange 29 is provided to move into overlapping relation with the plate 11 when the carrier 15 is swung into closed position. To guide flange 29 into overlapping relation with plate 11 it has a lower laterally bent corner 29a. Both flanges 29 and ear 28 are laterally offset slightly with respect to the metal in portion 30 of the carrier, as is shown in both Figs. 1 and 3. This offset at the root of flange 29 provides a stop which strikes the forward edge 11b of plate 11 and limits the closing movement of the valance carrier 15. The offset at the root of ear 28 also provides a stop which becomes effective when the valance carrier 15 is swung into open position, as shown in Fig. 4. In this position the stop at the root of ear 28 strikes the lower edge 11c of plate 11, thereby preventing the valance carrier 15 from moving into a position of substantially downward inclination. Thus a valance being positioned in, or held in, the carrier 15 will not accidentally fall out when the carrier 15 is open.

With the valance carrier 15 open, a valance can be inserted edgewise, as shown in Fig. 4. Back flange 25 is provided with a flared top 25a to facilitate insertion of the valance. Also the flange 25 is springy and yielding, and when unstressed, inclines toward front flange 24, as is best seen in Fig. 3. Thus the flange 25 is forced backwardly by the valance as it is inserted; and this arrangement of flange 25 provides for proper reception of the valance despite a degree of variation in its thickness, as well as providing for tight holding of the valance to secure it against rattling by the wind.

When the valance carrier 15 is swung into closed position shown in Figs. 2 and 3, the flange 29 moves beneath a projecting member 31 which may be formed integral with leg 17 of the head-bar support 16. Thus in the closed position of the valance carrier it is laterally supported by virtue of the flange 29 lying between plate 11 and member 31. Flange 29 is formed with a projecting vertical ridge 29a which snaps beneath a complementary formation at 31a to latch the valance carrier in closed position. The member 31 is sufficiently large and sufficiently springy to securely hold the carrier 15 in closed position, but of course, the carrier can be opened by the application of sufficient opening force.

It will be noted that the height of flange 29 and latch ridge 29a far exceeds the height of latch member 31. This permits the same standardized parts to be used for brackets intended for different heights or thicknesses of head-bars. Despite considerable variation in the level at which head-bar support 16 is welded to plate 11, latch member 31 will nevertheless properly cooperate with latching flange 29.

10 A vertical guideway for keeper 20 is provided by the opposing edges of legs 11 and 18 of head-bar support 16, together with a rectangular cut-out in shelf 19, as is seen in Figs. 1 and 6. The keeper 20 is of generally U-shape form, having a vertical portion 20a, a head 20b and a foot 20c. A pressed-out longitudinal rib 20d stiffens the keeper, and a pressed-out bulge 20e is adapted to strike the top of shelf 19 and limit downward movement of the keeper. A barb 20f is adapted to strike the under surface of shelf 19 to limit upward movement of the keeper and prevent its accidental removal.

25 The keeper 20 can be assembled with the bracket, as shown in Fig. 6, being first placed with portion 20a in a horizontal position and with foot 20c projecting downwardly through the slot in shelf 16. This is shown in dotted lines in Fig. 6. Then the keeper 20 is swung upwardly, as indicated by the arrows in Fig. 6 to bring the portion 20a into vertical position in the guideway. By forcibly depressing the keeper, the barb 20f yields and passes to a position beneath the shelf after which the springiness of the barb restores it sufficiently to prevent accidental removal of the keeper.

30 With the valance carrier in open position as shown in Fig. 4, a valance 26 is pushed in place by movement in the direction of the arrow attached to valance 26 in Fig. 4. Similarly a head-bar 35 is moved into place on shelf 16 by movement in the direction of the arrow attached to head-bar 35 in Fig. 4. While positioning the head-bar on the shelf, keeper 20 is held in an elevated position, as shown in Fig. 4. When the head-bar has been completely inserted, the keeper drops or is pulled down, so that its head 20b enters the head-bar groove or cut-out 35a as shown in Fig. 2. Thus the head-bar is held against accidental removal. If desired, the keeper 20 may be dispensed with and the head-bar held in place by screws inserted through holes 36 (2 shown).

35 The construction shown in Figs. 7 to 10 is so similar to the one already described that only the differences need be pointed out. This will be done with the aid of reference characters which, so far as applicable, are the same as or similar to those already used.

40 Welded or otherwise suitably secured to plate 11' is a curtain rod support designated as a whole by 40. This support is substantially Z-shaped, having a flange 40a which is welded or otherwise secured to plate 11', and having a grooved vertical flange 40b which is spaced laterally from plate 11'. The groove 40c of flange 40b is adapted to support one end of a curtain rod 41, as seen in Figs. 8 and 10. Projecting rearwardly from back flange 25' of valance carrier 15' is a horizontal finger 42 which, when the carrier 15' is closed, overlies curtain rod 41 and prevents its removal.

45 Head-bar keeper 20' is generally similar to keeper 20 already described, but does not have the barb 20f and does not have the protuberance 20e to limit downward movement of the keeper. The keeper 20' does, however, have two struck-

out spring fingers 44 and 45 and also has a struck-out protuberance 46.

The keeper 20' is movable in a vertical guideway similar to the one previously described, and which is formed in conjunction with head-bar support 18'. In this instance the head-bar support 18' has downwardly projecting legs 17' and 18' which are welded to plate 11'. The keeper 20' is assembled in its guideway in a manner similar to that shown in Fig. 6, except that it is inserted from beneath shelf 18' of the head-bar support 18', the head of the keeper being inserted first and the keeper being swung downwardly and then pushed upwardly into its guideway. When the keeper is pushed upwardly in its guideway spring finger 44 yields and then springs out again after the finger has passed above the shelf 18'. Thereafter finger 44 limits downward movement of keeper 20' and prevents its accidental removal. Upward movement of the keeper is limited by protuberance 46. When the keeper 20' is in its uppermost position shown in Fig. 9 spring finger 45 makes frictional engagement with the edge of the cut-out in shelf 18', thereby preventing the keeper from falling under the action of gravity. This is quite an advantage, as it holds the keeper out of the way during the insertion of the head-bar 35. As the head-bar is mounted on two brackets which may be widely spaced, it is awkward and inconvenient for an installer to manually hold the two keepers in uppermost position while the head-bar is being inserted.

In compliance with the patent statutes I have disclosed the best forms in which I have contemplated applying my invention but it will be understood that the forms disclosed are illustrative of the invention without limiting the scope of the invention.

What I claim is:

1. A Venetian blind bracket comprising: a vertical plate, and a laterally projecting flange at the rear of the plate for mounting the bracket on the forward face of a window frame, the vertical plate projecting beneath the bottom of the flange and having the rear edge of the projecting portion positioned flush with the rear surface of the flange.

2. A Venetian blind bracket comprising: a body member and a head-bar support having a guideway formed in connection therewith, a keeper vertically slideable in the guideway, and a pair of spring fingers, one higher than the other, attached to the keeper and adapted to engage the head-bar support, the keeper being insertable into the completed guideway and one spring finger acting to prevent accidental removal of the keeper from the guideway and the other spring finger acting to hold the keeper in position for the placing of a head-bar on said support.

3. A Venetian blind bracket comprising: a vertical plate, and a laterally projecting flange at the rear of the plate for mounting the bracket on the forward face of a window frame, the vertical plate projecting beneath the bottom of the flange and having the bottom part of the rear edge of the projecting portion positioned flush with the rear surface of the flange.

4. In a Venetian blind bracket having a vertical plate to be affixed adjacent to a window frame, and a valance carrier pivoted adjacent to the lower forward corner of the plate and swingable into open and closed position; the improvement which comprises: the valance carrier having a face which is flush with the outer surface

of the vertical plate, having a portion which abuts against the forward edge of the vertical plate when the valance carrier is in closed position, and also having two rearwardly extending vertically spaced portions which are laterally offset with respect to said abutting portion and each of which makes side-to-side engagement with the inner face of said vertical plate, one of said offset portions being at the lower forward corner of the vertical plate and the pivotal attachment between the carrier and the plate being to such offset portion.

5. In a Venetian blind bracket having a vertical plate to be affixed adjacent to a window frame, and a valance carrier pivoted to the plate and swingable into open and closed position; the improvement which comprises: the valance carrier having a face which is flush with the outer surface of the vertical plate, having a portion which abuts against the forward edge of the vertical plate when the valance carrier is in closed position, and also having two rearwardly extending vertically spaced portions which are laterally offset with respect to said abutting portion and each of which makes side-to-side engagement with the inner face of said vertical plate, the pivotal attachment between the carrier and the plate being to one of said offset portions.

6. In a Venetian blind bracket having a vertical plate to be affixed adjacent to a window frame, and a valance carrier pivoted adjacent to the lower forward corner of the plate and swingable into open and closed position; the improvement which comprises: the valance carrier having a portion which abuts against the forward edge of the vertical plate when the valance carrier is in closed position and which abuts against the lower edge of the vertical plate when the valance carrier is in open position to thereby limit the downward swing of the valance carrier, and the valance carrier also having a rearwardly extending portion which is laterally offset with respect to said abutting portion, the pivotal attachment between the carrier and the plate being to such offset portion.

7. In a Venetian blind bracket having a vertical plate to be affixed adjacent to a window frame, and a valance carrier pivoted adjacent to the lower forward corner of the plate and swingable into open and closed position; the improvement which comprises: the valance carrier having a portion which abuts against the forward edge of the vertical plate when the valance carrier is in closed position and which abuts against the lower edge of the vertical plate when the valance carrier is in open position to thereby limit the downward swing of the valance carrier, the valance carrier having a lower-positioned rearwardly extending portion which is laterally offset with respect to said abutting portion, the pivotal attachment between the carrier and the plate being to such offset portion, and the valance carrier also having an upper-positioned rearwardly extending portion which is laterally offset with respect to said abutting portion and which has a lower bent-away corner to guide it into side-by-side engagement with the inner face of the vertical plate.

8. In a Venetian blind bracket having a vertical plate to be affixed adjacent to a window frame, and a valance carrier pivoted adjacent to the lower forward corner of the plate and swingable into open and closed position; the improvement which comprises: the valance carrier having a face which is flush with the outer surface

of the vertical plate, having a portion which abuts against the forward edge of the vertical plate when the valance carrier is in closed position, and also having an upper-positioned rearwardly extending portion which is laterally offset with respect to said abutting portion and which moves alongside the inner face of the vertical plate as the valance carrier is closed.

9. In a Venetian blind bracket having a vertical plate to be affixed adjacent to a window frame, and a valance carrier pivoted adjacent to the lower forward corner of the plate and swingable into open and closed position; the improvement which comprises: the valance carrier having a face which is flush with the outer surface of the vertical plate, having a portion which abuts against the forward edge of the vertical plate when the valance carrier is in closed position, and also having an upper-positioned rearwardly extending portion which is laterally offset with respect to said abutting portion and which moves alongside the inner face of the vertical plate as the valance carrier is closed, the lower corner of said offset portion being bent away to guide it alongside the inner face of the vertical plate.

10. In a Venetian blind bracket having a vertical plate to be affixed adjacent to a window frame, and a valance carrier pivoted adjacent to the lower forward corner of the plate and swingable into open and closed position; the improvement which comprises: the valance carrier having a face which is flush with the outer surface of the vertical plate, having a portion which abuts against the forward edge of the vertical plate when the valance carrier is in closed position, and also having an upper-positioned rearwardly extending portion which is laterally offset with respect to said abutting portion and which moves alongside the inner face of the vertical plate as the valance carrier is closed, the vertical plate being provided with means spaced laterally from its inner surface and with which said offset means makes side-by-side engagement when the valance carrier is closed.

11. In a Venetian blind bracket having a vertical plate to be affixed adjacent to a window frame, head-bar supporting means projecting from one side of the plate, and a valance carrier pivoted adjacent to the lower forward corner of said plate and swingable into open and closed position; the improvement which comprises: the head-bar supporting means being provided with a forwardly projecting member which is laterally spaced from the inner face of the vertical plate, and the valance carrier being provided with means lying between said forwardly projecting member and the inner face of the vertical plate when the valance carrier is closed.

12. In a Venetian blind bracket having a vertical plate to be affixed adjacent to a window frame, head-bar supporting means projecting from one side of the plate, and a valance carrier pivoted adjacent to the lower forward corner of said plate and swingable into open and closed position; the improvement which comprises: the head-bar supporting means being provided with a forwardly projecting member which is laterally spaced from the inner face of the vertical plate, and the valance carrier being provided with a flange lying between said forwardly projecting member and the inner face of the vertical plate

when the valance carrier is closed, said flange and forwardly projecting member being formed as cooperating latch members acting to latch the valance carrier in closed position.

5 13. A Venetian blind bracket comprising: a vertical plate to be affixed adjacent to a window frame; head-bar supporting means projecting from one side of the plate; and a valance carrier pivoted adjacent to the lower forward corner of said plate and swingable into open and closed position, the carrier extending vertically along the front edge of the plate when in closed position, extending forwardly from the bottom of the plate when in open position, and carrying the valance fixedly attached to it as it swings from open to closed position and vice versa, the valance carrier also being provided with a latch formation cooperable with latching means positioned at different vertical levels on the vertical plate.

25 14. A Venetian blind bracket comprising: a vertical plate to be affixed adjacent to a window frame; head-bar supporting means projecting from one side of the plate; and a valance carrier pivoted adjacent to the lower forward corner of said plate and swingable into open and closed position, the carrier extending vertically along the front edge of the plate when in closed position, extending forwardly from the bottom of the plate when in open position, and carrying the valance fixedly attached to it as it swings from open to closed position and vice versa; the vertical plate being provided with a curtain rod support, and the valance carrier being provided with means which, when the carrier is closed, holds the curtain rod against removal.

30 15. A Venetian blind bracket comprising: a vertical plate to be affixed adjacent to a window frame; a head-bar supporting shelf attached to the plate and projecting laterally from one side of the plate; a valance carrier pivoted adjacent to the lower forward corner of said plate and swingable into open and closed position, the carrier extending vertically along the front edge of the plate when in closed position, extending forwardly from the bottom of the plate when in open position, and carrying the valance fixedly attached to it as it swings from open to closed position and vice versa; a latch formation formed integrally with the shelf and located at approximately the same level as the shelf; and a cooperating latch formation projecting from an upper part of the valance carrier; the two latch formations being cooperable to latch the carrier in closed position.

35 16. A Venetian blind bracket comprising: a vertical plate to be affixed adjacent to a window frame; head-bar supporting means projecting from one side of the plate; and a valance carrier pivoted adjacent to the lower forward corner of said plate and swingable into open and closed position, the carrier extending vertically along the front edge of the plate when in closed position, and extending forwardly from the bottom of the plate when in open position, and the valance carrier being provided with two laterally projecting members to receive the valance between them, one of the members being yielding whereby the members tightly grip an inserted valance even with a degree of variation in the thickness of the valance.

HARRY H. NELSON.
